UNITED STATES PATENT OFFICE.

JAMES HAYES, OF CLEVELAND, OHIO.

TOILET ACCESSORY.

1,302,038.

Specification of Letters Patent. Patented Apr. 29, 1919.

Application filed November 1, 1917. Serial No. 199,680.

To all whom it may concern:

Be it known that I, JAMES HAYES, a citizen of the United States, and resident of Cleveland, in the county of Cuyahoga and State of Ohio, have invented certain new and useful Improvements in Toilet Accessories, of which I hereby declare the following to be a full, clear, and exact description, such as will enable others skilled in the art to which

10 it appertains to make and use the same.

The objects of the invention are to provide a novel form of toilet accessory used as a protector for the clothing of those engaged in manual labor requiring the use of 15 fluids of all sorts, and in such operations as washing, painting, baking and chemical work where the clothing needs protection.

The device is designed for application to the wrists and coat sleeves and cuffs of the 20 operator and comprises preferably, an elastic tube or sleeve applied closely to the wrists which prevents fluid from entering underneath it.

It includes also a conical tube or member 25 attached thereto and preferably composed of water-proof material, a portion of which can be folded forward or reversed to form a guard and forwardly flaring annular cup that will catch any fluid running downward 30 from the hands when raised and keep it away from the clothing. The invention is hereinafter further described, shown in the accompanying drawings and specifically pointed out in the claims.

35 In the accompanying drawings Figure 1 is a side elevation of the device showing the parts extended, Fig. 2 is a similar view showing the guard in position for use; Fig. 3 is a longitudinal section thereof.

40 In these views A is an elastic sleeve applied to the wrist to exclude liquids therefrom. B is a cone formed of stiffened but flexible material, and attached to the inner end of the sleeve, and this member can be 45 folded forward at B², intermediate of its ends, to form an annular cup, which will catch and retain fluid when the hands are in the raised position, but will permit it to flow out when the hands are lowered. As

50 shown in Figs. 2 and 3 when the cone is extended as shown in Fig. 1, it can be slipped over the coat sleeve and cuff to protect them.

A limit for folding the conical guard is provided by means of elevated stop members D, D, which are attached to the guard

B and preferably extend longitudinally thereof and are provided with shoulders E, E. The margin of the guard B is preferably reinforced by means of a bead or ring C, of the same or similar material.

60

Having described the invention what I claim as new and desire to secure by Letters Patent is:

1. A sleeve protector, attachable to the wrist of the operator, consisting of an elastic tube, engaging the said wrist, a stiff conical guard, attached to said tube foldable on itself to form an outwardly flaring cup in a forward direction on a line intermediate of its ends, means of limiting the line of folding of the conical guard and means reinforcing the outer edge of said conical guard.

2. A sleeve protector comprising a stiff conical guard, said guard foldable intermediate of its ends to provide a flaring body and an annular cup at the outer end thereof, and means for limiting the position of the line of folding of said conical guard.

3. A sleeve protector comprising a stiff but flexible conical guard, said guard foldable intermediate of its ends to provide an outer annular cup, means for limiting the position of the line of folding of said conical guard, and an elastic tubular wrist attached to the inner end of said guard.

4. A sleeve protector comprising a stiff conical guard, said guard folded forward upon itself intermediate of its ends to form an outwardly flaring cup, spaced stiffening bars attached to the inner face of the cup, and extending from the fold to the margin thereof, and a bead encircling the outer edge of said cup.

5. A sleeve protector comprising a stiff conical guard, said guard folded forward upon itself intermediate of its ends to form an outwardly flaring cup, spaced stiffening bars attached to the inner face of the cup, and extending from the fold to the margin thereof, and a bead encircling the outer edge of said cup and a thin tubular elastic wrist portion attached to the smaller end of said conical guard.

105 In testimony whereof, I hereunto set my hand this 26th day of September 1917.

JAMES HAYES.

In presence of

S. W. SANGSTER,
Wm. M. MONROE.
